UNITED STATES PATENT OFFICE.

GEORGE HOLT FRASER, OF BROOKLYN, NEW YORK.

SEPARATOR AND THE LIKE.

Application filed April 28, 1915, Serial No. 24,396. Renewed February 6, 1922. Serial No. 534,592.

To all whom it may concern:

Be it known that I, GEORGE HOLT FRASER, a citizen of the United States, residing in the borough of Brooklyn, county of Kings, 5 city and State of New York, have invented an Improvement in Separators and the like, of which the following is a specification.

This invention relates to separators or sifters for separating fine material from coarse, 10 and aims to provide certain improvements therein.

Heretofore separators have been used with an inclined spring mounted screen over the top of which material to be screened has been 15 distributed so that it could flow down the screen cloth, the cloth being jarred to facilitate passage of the fine material through it and prevent clogging.

This invention aims to provide improvements in screens or separators especially applicable to the inclined screen type, and has for its objects to simplify such devices, facilitate their operation and manipulation, increase their efficiency and range of adjustment, and attain compactness with great 25 relative superficial screen surface.

To this end in carrying out the preferred form of the present improvements a sectional inclined screen surface is preferably provided, 30 comprising preferably a plurality of successive screen sections disposed one below another and preferably in different inclined planes so that they constitute a series of steps, in which case an interceptor, arrester or retarding dam is preferably provided below each step, impact members acting simultaneously on two adjacent sections are preferably employed, springs or supports for two adjacent sections are provided, improved 35 means for mounting, positioning and movably and adjustably carrying the screen sections are provided, and preferably means for adjusting the sections as a group in their angularity and means for relatively adjusting 40 their inclination independently are provided, and improved distributing, feeding, collecting, scalping and jarring means are provided, and various features of improvement 45 are provided, all of which will be more fully 50 hereinafter set forth.

In the accompanying drawings, which illustrate the preferred adaptation of my present improvements,

Fig. 1 is a vertical transverse section of 55 an inclined screen separator showing the preferred form of my invention;

Fig. 2 is a fragmentary side elevation thereof, and

Fig. 3 is a fragmentary front elevation thereof, partly broken away to show the interior and partly in vertical section cut approximately on line 3-3 of Fig. 1, through 60 the center of the head.

Fig. 4 is a fragmentary cross section cut on the line 4-4 of Fig. 1, Fig. 5 is a fragmentary cross section cut on the line 5-5 of Fig. 1, and Fig. 6 is a similar section cut 65 on the line 6-6 of Fig. 1, and looking in the direction of the arrows.

Fig. 7 is an enlarged fragmentary sectional view, cut on the same plane as Fig. 1, showing the spring on which the screens are resiliently mounted and showing details of the construction shown in Figs. 1 to 6.

Fig. 8 is an enlarged fragmentary cross-section view, cut on approximately the same plane as Fig. 6 and looking upwardly, showing details of the construction shown in Figs. 1 to 6;

Fig. 9 is an enlarged fragmentary plan or 80 face view looking downwardly on Fig. 7, with the covers removed;

Fig. 10 is a section similar to Fig. 1 showing a modification;

Fig. 11 is an enlarged transverse fragmentary cross-sectional view similar to Fig. 8, but showing a modified construction of 85 jarring device;

Fig. 12 is an enlarged fragmentary vertical sectional view of the modification shown 90 in Fig. 11;

Fig. 13 is an enlarged fragmentary cross-sectional view similar to Fig. 11, but showing another modification of the jarring device, and

Fig. 14 is an enlarged fragmentary vertical sectional view similar to Fig. 12, but showing the construction shown in Fig. 13.

Referring to the drawings let A indicate the main frame or casing, B the head feeder 100 or distributor, and C the screen or screens of a separator. Let D indicate the inlet for material to be screened, E the coarse outlet, F the fine outlet and G the jarring mechanism.

These parts may be of any usual or suitable construction and arrangement whereby the material to be screened will be delivered on top of the screens and fine and coarse products will be separately removed, the 110 screen being jarred or vibrated to prevent clogging during operation, but those shown

comprise improvements incident to my invention which will be hereinafter more fully set forth.

Referring to the drawings I will now describe in detail the preferred embodiment of my improvements as illustrated therein.

The main frame or casing A preferably comprises relatively adjustable members or elements the one carrying the screen or screens and the other supporting it so that the angle of inclination of one can be adjusted relatively to the other to vary inclination of the screen clothing. As shown the casing comprises fixed or stationary outside walls H mounted preferably immovably at the lower ends on feet a and at their upper ends on legs b, and on each is pivotally or removably mounted a back door or back wall I of relatively steep inclination, the side walls 15 being open in front and connected by a cross-member or angle c at the bottom constituting the partition between the coarse outlet E and the fine outlet F, and by a member or angle e at the top so that this element 20 of the casing constitutes an open rectangular frame or shell preferably of steeper inclination than the screen clothing.

As shown the other element of the casing or shell comprises movable or adjustable side walls J preferably hinged at f to swing within the outer side walls H, connected at their upper ends by a cross-member or T g and at the lower ends by a cross-member or angle h, and open at their bottom and top sides below 35 and above the screens, their outer lower edges being provided with a flange or member i to make rubbing contact with the fixed side H, to space the walls J therefrom and prevent leakage between these walls, and 40 their upper edges carrying the separable sectional covers j which are removably and swingingly mounted thereon and serve to close the front or top of the casing.

The head B is mounted on the upper end 45 of the fixed sides so as to be stationary therewith but separable therefrom.

When thus constructed the screen casing comprises an expandible shell composed of relatively movable telescopic members either 50 of which can be adjusted relatively to the other, or which together can be simultaneously moved to vary inclination of the casing. When the inner casing is adjustable the adjustment is preferably effected by a 55 screw or other adjusting device k.

The screen or screens C are preferably carried from the adjustable sides J of the casing and movable therewith and relatively thereto, being shown as movably and elastically supported therefrom by being spring 60 mounted thereon so that they will be shifted with the adjustment of the screen casing to vary their angle and may adjust themselves therein to suit the angularity requisite to the 65 stops, abutments or impact members posi-

tioning them and may yield or vibrate when jarred.

I prefer to construct the screen of a series or plurality of screen sections arranged one below the other in such manner that material flowing down the screens will pass from one to the next and to simultaneously jar the adjacent edges of two screen sections, and preferably I mount the successive screen sections in different planes each lower than the preceding one so that the screen clothing will be arranged in a series of steps and the material will fall from one to another in traveling down the screens. As shown each screen section consists of a rectangular frame or member l on which the screen clothing m is attached and suitably stretched by adjustable compression screen rods n having exposed screw heads or provisions o by which they can be turned from above and in front 85 of the screen, and these sections are superposed one directly on the next so that they make vibratory contact with one another to transmit from one to another the jarring effect and cause the adjacent edge of each to 90 assume its proper position relative to the adjacent impact post or positioning member K so that the latter may act on both sections preferably by acting through one to the other, and I provide a plurality of impact 95 posts K opposite the overlapping portions of adjacent screen sections, which preferably constitute the positioning abutments for holding the screen downwardly against the stress of their springs and have adjustable 100 shoulders p by varying which or by substituting posts of other dimensions position of the screens can be altered to increase the angularity of one and diminish that of an adjacent section, or to make impact contact uniform 105 across the screen, which shoulders abut against some part of the casing as the underside of the adjacent dam or the edges of two covers j, and project above the casing in the form of anvil heads q which may pass 110 through notches in the edges of the covers as shown into position to be acted on by the jarring mechanism. As shown any cover j may be swung upwardly or removed without interference from the adjacent anvil heads, 115 and each cover can be raised from either end or lifted bodily without disturbing the anvils or the other covers.

Any method of spring or other support for the screen or screens may be used, but according to the preferred form of my invention I provide leaf springs L for this purpose which are preferably mounted beneath the edges of the bars of the screen frame on a cross-bar r mounted on the sides J and carrying a plurality of springs L so disposed that their upper ends will receive the upper edges respectively of adjacent screen sections and through them sustain the lower edge of the next upper section, being here 120 125 130

provided with a hook or face which will engage the front of this edge to support the screen against forward descent so that the screen is elastically poised against descent in either direction, and the springs can adapt themselves to equalize their stress to the position of the screen. The bar *r* and springs *L* are provided for each screen section so that the springs of the lower sections each cross one frame and the adjacent edge of the next upper section and these lower series of springs thus assist in maintaining two adjacent sections while the uppermost series of springs at their upper ends serve to hold the upper edge of the first screen section suitably against the upper feed plate or member *e* which acts as a positioning abutment for this edge. The lowermost series of springs *L* serve to hold the lower edge of the lowest screen section upwardly against the lower post *K* which as here shown acts merely as a positioning abutment and is not acted on by the jarring mechanism.

My invention preferably provides an intermediate feed plate *M* at the top of each lower screen section for receiving material falling from the preceding section and deflecting it downwardly parallel with the screen clothing of the next section to save the latter from impact and wear from the falling material. This plate may be fastened on the upper edge of the lower section.

To prevent acceleration of flow affecting screening efficiency my invention provides means for retarding or arresting material flowing down the screen and redirecting it downwardly at reduced speed at one or more points throughout the screening surface. This is preferably accomplished by providing a plurality of screen surfaces set in succession as described and by providing a dam or retarder *N* beneath and spaced apart from the lower extremity or side of each section so that it will intercept material that has left the latter, change its course and direct it to the next lower section, and preferably onto the refeeding plate *M* thereof. The dam *N* is spaced in front of the section above it to allow a sufficient rearwardly and downwardly extending passage *s* for the material to descend between the screens and the dam and sufficiently above the next screen section to allow a refeeding passage *t* employed for the flow of material onto the next screen. Each screen will be so narrow that undue acceleration of down-flow will not occur before the material leaves the section, and the dam will be positioned to intercept the material, and by deflecting and redirecting it will so retard it as to cause it to slowly pass onto the next screen section, and in this manner undue acceleration of flow will be avoided and full screening efficiency may be attained.

65 While the dam or dams may be mounted

in any suitable manner I prefer to mount them movably so that they will follow the movement of the lower edge of the next upper screen or move therewith or with both adjusting edges or participate in the jarring thereof and be independent of and disconnected from both adjoining sections so that they may be removed without disturbing the dam.

70 My invention provides improved impact members *K* which are preferably movably and removably mounted on the adjacent dam as by having a male slideway *u* engaging tubular brackets *w* fixed on the dam and out of the plane of the adjacent screen, 80 so that the posts can be lifted off to permit swinging the screen up.

75 The jarring mechanism *G* may be of any construction adapted to vibrating jarring or oscillating the screen surfaces, and may be driven from any suitable source, but my invention provides an improved construction designed to facilitate easy access to the screen sections, and preferably comprises swinging strikers or hammers *O* above the 90 posts *K* which are preferably mounted on a rod or bar *P* extending from end to end of the casing *J* having portions or arms extending rearwardly outside thereof and pivoted to the sides thereof at a point between the 95 movable and fixed sides of the casing sufficiently low for the strikers to acquire an approximately horizontal position as they strike the posts so that gravity may be effectively used for giving a hammer blow with 100 the strikers despite the steep inclination of the screen casing. As shown the members *P* are U-shaped members or rods the legs of which are outside of the edges of the covers *j* and the center or cross-bar of which is opposite the meeting edges of two adjacent covers so that either cover can be moved without interference from the strikers and the screen frame can be entered or removed past the strikers.

105 110 The strikers are preferably swung or oscillated from the main driving shaft *Q* of the feeder, by any suitable swinging or lost motion device as for example the cam *v* operating the lever *x* and connecting rod *y*.

115 Material may be fed directly to the top screen section, but my invention provides an improved means for removing any large pieces and conducting these away outside of the main casing, an improved means for distributing the feed over the screen sections in a wide thin stream.

120 125 Preferably a coarse screen *R* disposed at an angle approximately at right angles to the fine screens is provided above the latter and a receiving plate *S* beneath this directs material fine enough to pass it through a conduit *z* onto the receiving plate or member *e* of the top screen, and a transverse tailings chute *T* crossing the upper end of the 130

casing directs coarser material away to the rear. The screen R is preferably slidingly removably mounted on the upper end of the main casing and the chute T is separably connected to the outer sides H, comprising channels or members U which are fixedly bolted thereto at their lower ends and separably attached to the head B at their upper ends to support the latter from the stationary casing so that the head will occupy a definite relation to the feet. A back door a' for the chute T permits observation of and access to the scalper screen R.

According to one feature of my improvements the head B comprises a vertically divided hopper W, a distributing conveyor X and a feed trough V having adjustable tilting or inclined edges front and rear over which the conveyor may discharge material coming from the hopper in a wide thin stream and distribute it from end to end of the screen. The head comprises a casing enclosing these parts and having feed spaces b' at front and rear of the trough and a front feed bar c', and rear feed bar d' spaced apart to give the outlet e' to the screen R, a swinging or removable semi-cylindrical cover f' separably mounted on longitudinal bars g' connecting the bearing ends Y and Z of the head. These ends are preferably sectional being parted vertically and the head Y being rigidly bolted to the arm U so as to be fixedly carried from the outer casing while the head Z is separably bolted to the head Y to be removable therefrom with the feed plate e' its bar g' and the hopper W so that one half of the head may be removed to expose the internal parts for removal or adjustment. On the inner face of each head Y and Z is a flange h' which supports the trough V and permits it to be oscillated or adjusted to distort its edge to change the inclination thereof for adjusting the distribution of material over the edge. The trough V lays on these flanges and is held thereon by a disc i' which fits in the trough and has a finger j' engaging a notch k' in the latter so that the trough can be rotated with the disc. This disc has a projection l' extending through a notch or slot m' in the heads and engaged by adjusting screws n' by which the disc can be turned. The disc is bored to fit the shaft Q and has a neck o' fitting a socket in the heads and a flange p' embracing the outer wall thereof to hold the disc axially in position.

Outwardly of the disc the heads have half round bearing sockets q' in which the lower half of the bearing sleeve or box fits and is held by a bolt s' to keep the box from lifting out so that it will be concentric with the head. A cap t' for this box is bolted thereto through side ears which fit in notches u' and in the bearing arm. A revolving washer

v' is keyed on the shaft between the disc and the bearing to prevent dust travelling along the shaft to the latter. Intermediate of its ends the trough has a reinforced casting w' on which is pivotally mounted an extra guard plate x' for preventing material entering the hopper from falling over the back side of the trough and on which also is mounted a reinforcing angle y' which can be tilted with the edge of the trough or independently of it to adjust the angle of the edge and later serve to keep the edge from opening up. The collars v' engaging the outer sides of the bearings serve as thrust collars for positioning the conveyor, and the drive pulley W' may be outside of either of these, this pulley and the shaft, conveyor and bearing heads and trough being reversible bodily or in direction of drive, and the hopper and cover being reversible. The abutting faces of the heads Y and Z and the disc i' make sufficiently intimate contact to prevent dust escaping through the slot m'.

In operation with the construction shown the outer casing will be adjusted to the position desired for the hopper elevation and then fixed in position. The inner casing will then be adjusted to give the desired angularity for the screens as a group. The knockers will be slackened, varied or adjusted to give desired relative angularity for each screen section, and the conveyor trough will be adjusted to properly distribute material. The driving pulley will revolve in either direction and material will be spread across the scalping screen and that fine enough pass through it to the fine screens down which it will flow successively being alternately retarded and re-fed in its passage to the coarse outlet. The fine material passing the screens will flow down the relatively steep bottom to the fine outlet. Impactive jarring of the screens will be transmitted through from one section to another to avoid clogging. Operation will be observed by lifting any front door, and any screen section will be removed through its corresponding door. To repair or replace a conveyor section the movable half of the head B will be disconnected thus exposing longitudinal parts for access or removal.

It will be seen that my invention provides improvements which can be readily and advantageously availed of and it will be understood that the invention is not limited to the particular details of construction, arrangement or combination of parts set forth as constituting its preferred form since my improvements can be availed of in whole or in part according to such modifications, adaptations or combinations as circumstances or the judgment of those skilled in the art may dictate without departing from the spirit of the invention.

One such modification is shown in Fig. 130

10 which is a section similar to Fig. 1, showing coil springs L' mounted in slotted sockets on the angles r of the swinging sides J and supporting the screens C , these springs 5 being adjustable by dropping washers in the sockets beneath the springs to increase their tension. The screen frames are here shown as supported forwardly by rollers a'' , and upwardly by the tubular brackets b'' through which the impact rods K' loosely operate, these being plane bars on the upper ends of which the hammers O strike. The upper hammer lever P' is here shown 10 as a link which is lifted by the cam v'' which is on a shaft opposite the junction of two screens and clears both adjacent covers j sufficiently to permit these to be removed.

The pulley for this shaft operates in the space between the sides J and H , and the 20 lever for the lower hammers is fulcrumed in this space and its upper end projects under and is operated by this cam.

In this construction the lower end of the lower screen is vibrated by a spring impelled impact post K'' , shown on a larger scale in Figs. 11 and 12, in which it will be seen that a coil spring c'' working in the tubular abutment guide b'' presses the post down in its guideway d'' when its roller e'' 25 is released by its cam f'' . This permits a very strong impactive blow, and the spring is shown as a little short to avoid constant pressure of the bar on the screen.

A step or horizontal cross-bar g'' is here 30 shown by which the operator can stand on the apparatus without danger of injuring or interfering with the operating parts.

In Figs. 7 and 8 the roller a'' is shown seated in a notch h'' in the bracket t'' , 40 which bracket has a curved top wall i'' fitting under the overlapping edge of the top screen and a curve or recessed wall j'' fitting over the upturned edge of the lower screen to prevent leakage between these. It 45 is also shown as having a side guide or hook k'' for guiding the upper and lower screens, and having a recess l'' for clearing the projecting clothing between them, and each of these springs is shown as united by 50 a sliding hook m'' by which they can be separably locked together to insure intimate contact and avoid bowing.

Figs. 13 and 14 show a jarring mechanism in which the bracket b^s is a single casting 55 extending through and notched out for the dam bar so that a long spring can be used. In this construction the bar has rollers at each side and is operated by two cams or a double cam to lift it. The bracket 60 has a notch or groove in which the spring holding pin slides, which prevents the post from revolving, and the upper end of the bracket is narrow to clear the cam.

In Fig. 10 all the impactive bars and the 65 dams are mounted on the top cover frame,

to swing upwardly with the latter as the top is swung on its hinge n'' situated just below the hinge f of the adjustable casing J .

What I claim is:

1. In combination, an inclined screen comprising two or more separably mounted similarly inclined successive relatively removable screen sections disposed successively in the direction of their inclination one below and in a lower plane than and 70 receiving material flowing over another, and jarring mechanism acting downwardly simultaneously on adjacent parts of two of said sections.

2. In combination, an inclined screen comprising two or more separably mounted similarly inclined successive relatively removable screen sections disposed one successively in the direction of their inclination one below and in a lower plane than and 75 receiving material flowing over another, and at their adjacent horizontally extending edges one removably sustaining another.

3. In combination, an inclined screen comprising two or more separably mounted 80 similarly inclined successive relatively removable screen section disposed one successive to another in their direction of inclination one below and receiving material flowing over another the adjacent horizontally extending portions of two of said sections being in removable contact and affording a closure between such sections.

4. In combination, an inclined screen comprising two or more separably mounted 85 similarly inclined successive relatively removable screen sections disposed successively in their direction of inclination one below and receiving material flowing over another, and a spring exerting an upward stress against adjacent parts of two of said sections.

5. In combination, a casing forming an inclined chamber, a removable inclined screen movably mounted in said chamber, adjustable supporting means on which said screen is resiliently and removably mounted adjustably mounted on said casing and adjustable to vary the inclination of said screen therein, means for movably positioning said screen relatively to said supporting means, means for jarring said screen relatively to said supporting means, means above said screen for directing material to be screened over said screen in the direction 110 of its inclination, and retarding means above said screen movable with and sustained by said supporting means and disposed in the path of such material for retarding its speed of flow over said screen.

6. In combination, an inclined screen comprising two two or more separably movably and resiliently mounted similarly inclined screens disposed successively in their direction of inclination one below and in a dif- 115 120 125 130

ferent plane than and receiving material flowing over another, having adjacent horizontally extending portions, means for jarring two of said screens, and a movable member intermediate of adjacent portions of two of said screens for receiving material flowing over an upper screen and diverting it on to the next lower screen disposed in operative relation to two of said screens for transmitting the vibration of their adjacent portions from one to another.

7. In combination, an inclined screen comprising two or more separably movably and removably mounted similarly inclined screens disposed successively in the direction of their inclination one below and in a lower plane than and receiving material flowing over another, means for jarring said screens, a bar as to which said screens are respectively movable and removable spaced apart from and disposed below the lower edge of an upper screen and above the upper portion of a lower screen for receiving and retarding material flowing over such upper screen and diverting it on to said lower screen, and means opposite and below said bar resiliently sustaining adjacent portions of two of said screens.

8. In combination, a screen comprising a casing having side members, an inclined screen mounted intermediate of said side members, jarring mechanism for said screen, and swinging hammers comprising U-shaped members pivoted to said casing at the sides of said screen and extending across said casing opposite said jarring mechanism near the edge of said screen, whereby the latter can be removed intermediate of the arms of said swinging members.

40 9. In combination, an inclined screen, having upper and lower edges and movable and removably mounted, a casing therefor comprising side members, impact posts engaging one of said edges of said screen, and strikers acting on said posts and disposed opposite the edge of said screen whereby the latter can be moved past said strikers.

50 10. In combination, an inclined screen, a casing therefor comprising adjustable members on which said screen is mounted and stationary members on which said adjustable members are mounted, a bottom wall carried by said stationary members, and a top wall movable relatively to said bottom wall and carried by said adjustable members.

60 11. In combination, an inclined screen, a casing therefor comprising open topped side walls between which said screen is removably mounted, impact posts above said casing acting on said screen, and two separably movable covers closing the top of said casing having their adjacent edges near the line of said posts and above and below the latter respectively.

65 12. In combination, an inclined screen, a

casing therefor comprising an open top member within which said screen is mounted, posts engaging the top of said screen and positioning it in said casing, and a movable top for the top of said casing movable relatively to said casing and holding said posts to position said posts.

13. In combination, an inclined screen, means for jarring said screen, a casing affording a chamber for said screen comprising a bottom wall below said screen, a top above said screen, and relatively movable complementary side walls intermediate of said top and bottom walls lapping and co-acting to afford expansible side walls at the sides of said screen affording a closure for said casing at the sides of said screen.

14. In combination, a casing providing an inclined chamber having an open upper end, a removable inclined fine screen mounted in said chamber, a second casing providing an inclined chamber having an open lower end communicating with and separably mounted on the upper end of said first casing, a second inclined screen mounted in said second chamber for delivering screened material to said first screen, leak preventing means overlapping and affording a recess for receiving the upper edge of said first screen and below said second screen receiving screened material from said second screen and diverting it in the direction of inclination of and on to said fine screen, and means above and extending past said fine screen providing a conduit from said second chamber to without said first chamber for receiving coarse material passing over said second screen and conducting it out of contact with said first screen.

15. In combination, a casing providing an inclined chamber, a removable inclined screen mounted in said chamber comprising an expansible frame and a screen clothing mounted thereon, a retarding member mounted in said chamber below and spaced apart from the lower edge of said screen, and means for adjusting the tension of said screen clothing by expanding said frame comprising a compression member between the upper and lower parts of said frame for expanding these having a portion for operating it exposed below and accessible beneath the lower edge of said frame and the adjacent part of said retarding means.

16. In combination, an inclined removably mounted screen comprising a horizontally expansible frame and a screen clothing mounted thereon, a casing providing a chamber and comprising side walls spaced apart from the sides of said frame and affording a space for expansion of said frame, and means for expanding said frame horizontally to vary the tension of said clothing comprising a horizontally extending compression member between the side members to said

frame and having a screw thread and a portion exposed and accessible in the space between the side of said frame and said side walls by which to adjust said member without removing said frame, and said frame having a screw thread engaged by said first mentioned screw thread for expanding said thread.

17. In combination, an inclined screen and
10 a casing therefor comprising an inclined top wall, and an impact post engaging the top of said screen and comprising an adjustable sliding member interposed between said screen and the top wall of said casing and
15 projecting above and adjustable relatively to the top wall of said casing.

18. In combination, an inclined resilient

removable screen, a second inclined screen above said resilient screen and having a lower part overlapping the latter, and means 20 intermediate of the lower part of said second screen and the upper part of said first screen for receiving material from the upper one and directing it on to the lower one for preventing leakage of material over the upper edge of said lower screen and one of said screens movable relatively to the other.

In witness whereof, I have hereunto signed my name in the presence of two subscribing witnesses.

GEORGE HOLT FRASER.
